Atty.

UNITED STATES PATENT OFFICE.

HOWARD G. BARTLING, OF CHICAGO, ILLINOIS, ASSIGNOR TO PEERLESS PNEUMATIC SYSTEMS, INC., OF CHICAGO, ILLINOIS, A CORPORATION OF ILLINOIS.

SPRAY GUN.

Application filed November 24, 1922. Serial No. 603,057.

To all whom it may concern:

Be it known that I, HOWARD G. BARTLING, a citizen of the United States, residing at Chicago, in the county of Cook and State 5 of Illinois, have invented certain new and useful Improvements in Spray Guns, of which the following is a specification.

This invention relates to improvements in spray guns, and has for its object to provide a new and improved gun in which the quality of the "brush" or jet may be regulated by changing the nozzle orifice, and for this purpose I provide a plurality of interchangeable nozzles having different sized 15 orifices therethrough.

In the accompanying drawing I have illustrated one embodiment of my invention, in which—

Figure 1 is a side elevation of my improved spray gun, a portion thereof being shown in section for clearness;

Fig. 2 is a front elevation of one of the removable nozzles;

Fig. 3 is a similar elevation of another nozzle; and

Fig. 4 is a vertical section, taken on the line 4—4 of Fig. 3.

Like numerals refer to like elements in the drawing, in which—

10 indicates a spray gun having an actuating trigger 10^a. An air supply tube 11 is attached to the gun, as is a liquid supply tube 12, it being customary to supply air and liquid under pressure to the gun through the respective tubes. At the front of the gun is constructed an air duct 10^b, through which projects the liquid duct 10^c, the flow of liquid therethrough being normally cut off by the slide valve 10^d. The end of the 20 air gun is provided with a plurality of air passages 10^e leading to an air chamber 13^a in the cap 13 from the air duct 10^b. The ends of the liquid duct projects into the cap, and is also threaded at its extremity for engagement by the apertured tip 14 containing a tapered aperture, through which extends the needle valve 10^f formed as a continuation of the valve 10^d.

The air chamber 13^a is continued around the tube 14 concentric therewith, and in the end of the cap 13 is threaded the nozzle 16 having an orifice 16^a surrounding the dis-

charge extremity of the tube 14. The cap is provided with projecting horns 13^b, which carry angularly formed air ducts 13^c leading from the air chamber 13^a, the function of these ducts being to flatten the spray stream, as is well known in the art.

The nozzles 16 are each provided with an enlarged knurled periphery 16^b for ready engagement by the fingers of the operator. In Figs. 2 and 3 I have illustrated two of the nozzles having different sized orifices.

In practice, when a batch of paint or varnish is replaced, it frequently happens that there is a variation in consistency, and this variation may perceptibly and seriously affect the quality or character of the "brush" or spray obtained. Previously it has been necessary for the operator to alter the consistency of the batch to overcome this objection, or in some instances a different color nozzle 14 may be substituted, either of which operations affect the labor cost and consume considerable time.

With my improved gun it is merely necessary to change the nozzle 16 to provide a different sized orifice. It will be obvious that when the substituted orifice is of lesser diameter the amount of air passing through the ducts 13^c will be increased, with a consequent variation in flattening of the jet. Likewise when a larger orifice is substituted less flattening air will flow, decreasing the flattening effect upon the spray. In this manner the character or quality of the "brush" or jet may be readily varied without materially affecting the quality of air used, and with easy and relatively small consumption of the operator's time.

I do not wish to be restricted to the specific form or character of my invention described in the above specification and embodied in the accompanying drawing, save as defined in the appended claims.

I claim:—

1. In combination in a spray gun, a cap having a main air passage duct and auxiliary flattening air ducts, and an easily removable nozzle member having an orifice therethrough and engageable with said cap, said orifice forming an outlet for said main air passage duct.

2. In combination in a spray gun, a cap

having a main air discharge duct, the cap being formed with projecting portions, auxiliary angularly formed air ducts in said portions leading from said discharge duct and constructed to deliver flattening jets upon air discharging from said main duct, and an easily removable nozzle member en-

gageable with said cap having an orifice in communication with and forming an outlet for said main discharge duct. 10

In testimony whereof, I have subscribed my name.

HOWARD G. BARTLING.
